WARM CONVERTER FOR LIQUEFIED GASES
OF LOW BOILING POINT

Leo I. Dana, Buffalo, N. Y., assignor, by mesne assignments, to Union Carbide and Carbon Corporation, a corporation of New York

Application March 20, 1934, Serial No. 716,447

12 Claims. (Cl. 62—1)

This invention relates to warm converters for liquefied gases of low boiling point and particularly to warm converters which have pressure vessels provided with spaced thin-walled linings 5 or baskets for holding a charge of liquefied gas that is to be converted into vapor.

The invention has for its object generally an improved construction and arrangement of parts whereby warm converters of the character indicated are adapted to receive and vaporize charges of low boiling point liquefied gases such as liquid oxygen, liquid nitrogen and the like, and to convert the same quickly and economically into vapor while maintaining the filling losses at a relatively low value.

More specifically, it is an object of the invention to provide warm converters having baskets with means for producing overflow from the basket into the clearance space about the basket in a desired manner, at a desired time.

It is another object to provide manually manipulated means in converters of the character indicated, for causing the overflow passage of liquid into the clearance space when desired, whereby vaporization of the charge of liquefied gas may be made to take place in advance of normal to any desired extent.

It is a still further object to provide an improved method of operating converters of the character indicated in a manner in which the rate-characteristic of vaporization may be accelerated at will.

Other objects of the invention will in part be obvious and will in part appear hereinafter.

The invention accordingly comprises the features of construction, combination of elements, and arrangement of parts, which will be exemplified in the construction hereinafter set forth and the scope of the application of which will be indicated in the claims.

For a fuller understanding of the nature and objects of the invention reference should be had to the following detailed description taken in connection with the accompanying drawings, in which:

Fig. 1 is a fragmentary vertical section through a warm converter constructed in accordance with the invention;

Fig. 2 is an enlarged detailed perspective view of the form of manually manipulated means employed for causing an overflow passage of liquid into the clearance space in the converter shown in Fig. 1;

Fig. 3 is another fragmentary sectional view showing a modified form of warm converter constructed in accordance with the invention; and

Fig. 4 is an explanatory diagram.

Referring now to the drawings and particularly to Fig. 1, the converter shown comprises a thick-walled outer vessel 10, commonly referred to as

a pressure vessel, which has a removable cover 11 and an inner spaced thin-walled lining or basket 12; this latter is preferably suspended in place from its upper end and is arranged to provide communication between the clearance space 5 about the basket and that within the basket in any convenient manner, for example, by means of perforations formed about the top as shown at 13. The cover 11 is conveniently provided with a filling opening 14 that is normally closed, 10 which closure may be accomplished by means of a removable plug that is normally in place when in operation. The warm converter is arranged to receive heat conductively from any suitable heat supplying means arranged on the exterior, for 15 example, from a water bath, as depicted at 15. While a water bath is commonly used with this type of converter and is shown in Heylandt Patent Reissue 18,476, dated May 17, 1932, it is obvious that other forms of warming means may be 20 used; such means comprising no part of the present invention.

In order to obtain a regulated overflow passage of liquefied gas from the space within the basket 12 into the clearance space on the exterior thereof, 25 a manually manipulated means, which is adapted to be moved so as to contact the liquid in the basket and cause this passage by displacement or otherwise, is provided. A reciprocating liquid displacing element 16 is here depicted on the 30 under side of the cover 11 near the top of the space within the basket 12, as a suitable form of means adapted to be moved downwardly at will to cause the desired passage of liquid. This reciprocating element or contactor preferably has 35 the form of a metallic pan provided with up-standing sides 17, as shown in Fig. 2, this pan having an interior spider 18 and supporting nipple 19 which is swiveled or otherwise secured to an actuating stem 20, that is passed through 40 the cover 11 to the exterior thereof for manual manipulation. The cover 11 preferably has a gland 21 secured therein for the purpose of making the passage of this stem through the cover a gas-tight one; this stem 20 may also advantageously have screw-threaded engagement with the gland 21, as shown at 22. A manual manipulating wheel 23 is provided at the outer end. A gas phase withdrawal connection is also provided for 45 the converter, as shown at 24.

In operation, a charge of liquefied gas is first introduced into the converter through the opening 14, which is then closed and heat applied to the walls of the converter. To accelerate the 50 normal conversion of the gas material from the liquid phase into the gas phase, the hand wheel 23 is moved to cause the contactor 16 to move from its uppermost position down into the liquid 55 in the basket 12. Since the converter is normally filled with liquid to a height slightly below 60

the openings 13, it is seen that a slight downward movement of the contactor 16 causes the same to contact with the liquid and raise the level to a point such that an overflow passage through the openings 13 into the clearance space takes place, the liquid then coming into contact with the warm walls of the vessel 10, where it becomes a rapidly boiling mass. Rapid conversion of liquid in basket 12 into gas follows, by reason of the forced passage of liquid into the clearance space.

By referring to Fig. 4, the degree of acceleration achieved by this forced passage can be readily seen. Here a time-pressure curve is shown at *a* depicting the characteristic manner in which pressure normally builds in the converter without the use of the liquid contacting means here provided. It is seen that the pressure initially rises slowly, then it rises at an increasing rate, which after a time becomes almost vertical and tapers off at the top with a portion of the curve that asymptotically approaches the horizontal. The steep portion of the curve represents the rate at which pressure builds when overflow through the openings 13 normally takes place, due to expansion of the liquid which is being converted in the basket. When the contactor is moved to cause overflow passage of liquid into the clearance space in advance of normal, the rate of pressure building is accelerated in the characteristic manner indicated in the curve depicted at *b*. Here it is seen that the time of the relatively slow initial building is much shortened and the rapid rise due to the overflow passage of liquid into the clearance space, takes place at an earlier time, the curve finally having an upper portion bending over, which asymptotically approaches the horizontal. While curve *b* is here depicted as midway between the initial time and the time at which the rapid building of pressure takes place in curve *a*, this position is, of course, variable and changes with each change of relative position and instant of time when the contactor 16 is moved with respect to the liquid. In consequence, it will be seen that the adjustable contactor provides means for accelerating the building of pressure within the converter in substantially any desired amount.

In the modified form of converter shown in Fig. 3, an outer thick-walled pressure vessel 30 is shown having a cover 31 and an inner spaced thin-walled vessel or basket 32. This basket is also supported and arranged in a manner which provides communication between the clearance space and the space within the basket; communication being preferably provided by means of suitable openings, which may be in the form of vertical sleeve passages 33, that perform an additional function, as hereinafter pointed out.

The basket 32 here provided differs from the basket shown in Fig. 1 in that a relatively large opening 34 is formed in the basket near the bottom thereof and is arranged to have the passage of liquid therethrough controlled by an obturating element 35, which is carried by a dish-shaped liquid contacting element 36 that is arranged to have limited vertical movement in the clearance space below the basket so as to move into and out of a position fitting closely about the basket and cause the obturating element to close and open the opening 34, whereby the overflow passage of liquid into the clearance space may be stopped or made to take place at will. The movement of the contactor 36 is controlled from the exterior of the converter in any convenient

manner, for example, by means of a vertically movable spider 37 mounted in the top of the converter on the under side of the cover 31, the spider having small chains or cables 38 for connecting the extremity of its arms respectively with points of support 39 on the rim of the contactor 36.

To move or reciprocate the spider, a screw-threaded stem 40 is passed through the cover 31 by means of a gland 41 and has swivel connection with the spider at 42, rotation of the spider being prevented in any convenient manner, for example, by means of a stop, as shown at 43, depending from the cover 31. The cover is also shown as provided with a filling opening 44 that is normally closed, and with a gas phase withdrawal connection 45.

In operation, the characteristic rise of pressure is similar to that shown in Fig. 4. When the obturator 35 is moved to close entirely the opening 34, the basket may be filled with liquid to the desired level without any passage of liquid to the clearance space. When the filling operation is over, the opening at 44 is closed and the pressure building operation begins. The rise of pressure is accelerated in advance of the normal rate of building as indicated by the relative positions of the curves *a* and *b* in Fig. 4, by causing the contactor 36 to move so that liquid passes from the basket into the clearance space in contact with the metal. The metal contactor is capable of storing an appreciable amount of heat which it imparts during this passage of liquid. The liquid, in consequence, is in a state of ebullition when it contacts with the interior wall of the vessel 30. The pressure rise, in consequence, thereafter is rapid. The volume of liquid passed in this manner is, of course, regulated by the position and instant of application of the contactor 36 in the same manner as does the movement of the contactor 16, which also has appreciable heat storage capacity and imparts its heat when it contacts with the liquid.

Since certain changes may be made in the above construction and different embodiments of the invention could be made without departing from the scope thereof, it is intended that all matter contained in the above description or shown in the accompanying drawings shall be interpreted as illustrative and not in a limiting sense.

Having described my invention, what I claim as new and desire to secure by Letters Patent, is:

1. In a warm converter for liquefied gases of low boiling point, the combination with a relatively thick-walled pressure vessel, of an interiorly disposed thin-walled basket spaced from the wall of said pressure vessel and forming a narrow unsealed clearance space about the same, said basket having means affording communication between the space within the basket and said clearance space, and liquid contacting means for causing an overflow passage of liquid from the space within the basket to said clearance space.

2. In a warm converter for liquefied gases of low boiling point, the combination with a relatively thick-walled pressure vessel, of an interiorly disposed thin-walled basket spaced from the wall of said pressure vessel and forming a narrow unsealed clearance space about the same, said basket having means affording communication between the space within the basket and said clearance space, and movable means for con-

- taacting the liquid in said basket and causing an overflow passage of liquid into said clearance space.
3. In a warm converter for liquefied gases of low boiling point, the combination with a relatively thick-walled pressure vessel, of an interiorly disposed thin basket spaced from the wall of said pressure vessel and forming a narrow unsealed clearance space about the same, said basket having means affording communication between the space within the basket and said clearance space, and means for storing an appreciable amount of transmittable heat adapted to cause an overflow passage of liquid from said basket into said clearance space.
4. In a warm converter for liquefied gases of low boiling point, the combination with a relatively thick-walled pressure vessel, of an interiorly disposed basket spaced from the wall of said pressure vessel and forming a narrow clearance space about the same, said basket having means adjacent its top affording communication between the space within the basket and said clearance space, and movable metallic means for contacting the liquid in said basket and accelerating the building of pressure in said vessel to a rate in advance of normal.
5. In a warm converter for liquefied gases of low boiling point, the combination with a relatively thick-walled pressure vessel, of a thin-walled basket supported at its upper end within said vessel and spaced from the wall thereof and provided with openings about the upper end whereby communication is established between the space without said basket and the space within the same, a removable cover for said pressure vessel whereby the same may be hermetically sealed, and a movable liquid displacing element supported by said cover within said basket and adapted to be forced into contact with the liquid in said basket and cause an overflow of liquid through said openings into the space about said basket.
6. In a warm converter for liquefied gases of low boiling point, the combination with a relatively thick-walled pressure vessel, of a thin-walled basket supported at its upper end within said vessel and spaced from the wall thereof and provided with openings about the upper end whereby communication is established between the space without said basket and the space within the same, a removable cover for said pressure vessel whereby the same may be hermetically sealed, a movable metallic liquid displacing element, means for operably securing said element within said vessel below the cover, and manually manipulatable means on said securing means for operating the same from the exterior of said vessel.
7. In a warm converter for liquefied gases of low boiling point, the combination with a relatively thick-walled pressure vessel, of a thin-walled basket supported at its upper end within said vessel and spaced from the wall thereof and provided with openings about the upper end whereby communication is established between the space without said basket and the space within the same, a removable cover for said pressure vessel whereby the same may be hermetically sealed, and a reciprocable metallic plunger suspended from said cover within said vessel and provided with manual means manipulated from the exterior of
- said vessel for moving said plunger into contact with the liquid within said vessel at will.
8. In a warm converter for liquefied gases of low boiling point, the combination with a relatively thick-walled pressure vessel, of an interiorly disposed thin-walled basket spaced from the wall of said pressure vessel to provide a relatively narrow unsealed clearance space about the same and provided with an opening near the bottom thereof to afford the passage of liquid from said basket into said clearance space, an obturating element for controlling said passage, and extended means for contacting liquid in the course of said passage.
9. In a warm converter for liquefied gases of low boiling point, the combination with a relatively thick-walled pressure vessel, of an interiorly disposed thin-walled basket spaced from the wall of said pressure vessel to provide a relatively narrow unsealed clearance space about the same and provided with an opening near the bottom thereof to afford the passage of liquid from said basket into said clearance space, an obturating element arranged to be moved into and out of said opening, and extended movable metallic means supporting said obturating element.
10. In a warm converter for liquefied gases of low boiling point, the combination with a relatively thick-walled pressure vessel, of an interiorly disposed thin-walled basket spaced from the wall of said pressure vessel to provide a relatively narrow unsealed clearance space about the same and provided with an opening near the bottom thereof to afford the passage of liquid from said basket into said clearance space, an obturating element arranged to be moved into and out of said opening, a movable metallic support for said obturating element having an extended surface adapted to fit snugly about the lower end of said basket, and means operable from the exterior of said vessel for moving said obturating element and said supporting means.
11. The method of operating a warm converter having a thick-walled pressure vessel provided with a spaced inner basket having communication between the spaces within and without said basket and adapted to convert liquefied gases of low boiling point into vapor by the application of heat externally, which method comprises filling the converter with liquefied gas to a desired liquid level, and causing at will the passage of liquid from said basket into the clearance space in advance of that normally taking place by the expansion of liquid during vaporization.
12. The method of operating a warm converter having a thick-walled pressure vessel and a spaced inner basket provided with openings disposed adjacent a desired liquid level and affording communication between the spaces within and without said basket and means for applying heat externally whereby liquefied gases of low boiling point may be vaporized in the converter, which method comprises filling the converter with liquefied gas to the desired liquid level, permitting normal passage of liquid from said basket into the clearance space when the liquid expands due to the application of heat, and accelerating said passage at will by causing additional liquid displacement from said basket.

LEO I. DANA.
